GARMENT

Ada Quinn, Ogden, Utah; Robert N. Quinn, executor of said Ada Quinn, deceased, assignor to Quinn Garment Company, Ogden, Utah, a partnership composed of Robert N. Quinn and Horace A. Quinn

Application June 21, 1944, Serial No. 541,397

16 Claims. (Cl. 2—52)

1

This invention relates to women's and children's garments which are suspended over the shoulders of the wearer and provided with a back panel or the like which is adjustable vertically according to the size of the wearer. For example, the invention may be embodied in adjustable aprons of the general type shown in my prior Patent No. 1,839,262, and for convenience is described hereinafter with reference to such garments, but it will be understood that the invention is not restricted to this particular use.

In Patent No. 1,839,262, the back panel of the apron is provided with a vertical strap which is stitched down to the panel at spaced points so as to provide separate loops, and the tie strings are inserted in any one of these loops at the choice of the wearer. However, adjacent loops are separated in the vertical direction only by the line of stitching so that the amount of adjustment obtained by using one loop in preference to another is quite small and in many cases insufficient for satisfactory results. Moreover, the stitching tends to pull out in service, particularly in the case of aprons and the like which are made of relatively light materials. Other arrangements of this same general type have been proposed, and these various proposals have met with varying degrees of success from the standpoints of convenience to the wearer, attractive and pleasing appearance, sufficient adjustability and strength, etc., all of which are important to the success of the garment in the market.

Among the objects of the present invention are to provide an improved adjustable back construction which embodies a satisfactory degree of adjustability and combines strength and long life with convenience to the wearer, attractive appearance, and economy of materials and simplicity of construction with consequent low cost. These and other objects will appear more specifically in the following description.

Several embodiments of the invention have been illustrated in the accompanying drawings in connection with an apron of the type mentioned above, but it is to be expressly understood that said drawings are for purposes of illustration only and are not to be taken as a definition of the limits of the invention, reference being had to the appended claims for this purpose.

In the drawings,

Fig. 1 shows an apron embodying the invention;

Fig. 1a is a detail view of the back construction of the apron shown in Fig. 1;

Figs. 1b and 1c respectively are sections on the lines 1b—1b and 1c—1c of Fig. 1a;

Fig. 2 is a detail view of another back construction embodying the invention;

Figs. 2a and 2b respectively are sections on the lines 2a—2a and 2b—2b of Fig. 2;

2

Fig. 3 is a detail view of a further back construction embodying the invention;

Figs. 3a and 3b respectively are sections on the lines 3a—3a and 3b—3b of Fig. 3;

Fig. 4 shows a still further back construction embodying the invention;

Figs. 4a and 4b respectively are sections on the lines 4a—4a and 4b—4b of Fig. 4;

Fig. 5 shows another embodiment of the invention;

Figs. 5a and 5b respectively are sections on the lines 5a—5a and 5b—5b of Fig. 5;

Fig. 6 illustrates still another embodiment of the invention; and

15 Figs. 6a and 6b respectively are sections on the lines 6a—6a and 6b—6b of Fig. 6.

The front of the garment may have any desired size and shape, and the garment extends over the shoulders of the wearer in any suitable manner as by means of a yoke, shoulder straps, etc., and then down the back, terminating in the loop construction hereinafter described. For purposes of example, Fig. 1 shows an apron 1 provided with shoulder straps 2 and suitable tie strings 3.

20 The ends of the shoulder straps 2 are secured to and carry what may be termed for convenience a loop member the details of which are shown in Figs. 1a, 1b and 1c, whereby the tie strings 3 are inserted in any one of a plurality of vertically spaced loops at the choice of the wearer and are then tied as indicated in Fig. 1.

The loop member comprises a single piece of material 4 which is folded over at the bottom 5 to form a double thickness, the two upper ends 35 being suitably secured at the top to the shoulder straps 2. The outer fold of the loop member tapers upwardly to a narrower width at the top than the inner fold and is split longitudinally throughout most of its length, part of the material being removed along the split to provide a pair of relatively narrow laterally spaced loop straps 6. Preferably the edges of the shoulder straps 2 and of the loop material 4 and loop straps 6 are bound with tape 7, which may be of contrasting color to provide a pleasing decorative effect. As shown in Fig. 1b, the ends of the shoulder straps 2 are turned back and secured by a single seam 8 with the upper edge of the inner fold 4 and the ends of the loop straps 6,

40 this seam preferably being bound with a continuation of the tape 7 of the outer edges of the shoulder straps 2.

The loop straps 6 are also divided vertically to provide for insertion of the tie strings 3 at vertically spaced points by means of a piece of material extending transversely across the outer sides of the loop straps and preferably having a substantially rectangular shape with substantial vertical extent to provide the desired adjustability.

tained by a rectangular strip 9 which secures the loop straps together over a central area of substantial vertical extent, said strip extending across the outer sides of the loop straps and being secured thereto by upper and lower horizontal stitchings 10, the ends of the strip being secured under the binding tapes 7 along the outer edges of the loop straps as indicated at 11. For decorative effects the strip 9 may be of a different color than the inner fold 4 and loop straps 6, preferably matching the tape 7.

The vertical extent of the said area, i. e., of the strip 9, should be on the order of an inch to an inch and a half. With this construction either the portions of the loop straps above the strip 9 or those below the strip may be used for the tie strings, these portions being separated by the substantial vertical extent of the strip to provide a correspondingly large adjustment of the garment. Moreover, the strip 9 acts as a reinforcement over the central area provided for adjustability and of itself bears a large part of the pull against the tie strings when the garment is being worn, thus relieving the stitchings 10.

Also the loop straps 6 are separated from the inner fold 4 of the loop member throughout the entire vertical extent of the latter, i. e., from the bottom fold line 5 to the transverse tape 7 and seam 8 at the top of the loop member. This construction enables the wearer to separate the loop straps from the inner fold easily for insertion of the tie strings, which is also facilitated by the lateral spacing of the loop straps along the vertical center line. The narrower outer fold enables the wearer to distinguish the folds by the sense of touch and to insert the tie strings without fumbling, and the taper of the outer fold also enables the wearer to distinguish readily between the upper and lower pairs of loops. On the other hand, the greater width of the inner fold 4 and of the fold 5 at the bottom of the loop member prevents it from doubling over when the strings are tied and provides body to maintain its shape and also its position on the body of the wearer.

Instead of forming the loop member by folding over a single length of material at 5 as described above, it may be desirable in some instances to make the inner and outer thicknesses of the loop member from separate pieces of material as illustrated in Figs. 2, 2a and 2b. The shoulder straps 12 are secured at their lower ends to the inner thickness or fold 13 of the loop member whereas the outer thickness or fold 14 comprises a separate piece of material the lower edge of which is secured to the lower edge of the inner fold 13. Preferably the tape 15 along the outer edges of the shoulder straps is continued around the edges of the inner fold 13 of the loop member, forming at the same time a bottom seam 16 between the loop folds 13 and 14. The outer fold 14 is split longitudinally as above described to form the loop straps 17 and the upper ends of these loop straps together with the upper edge of the inner fold 13 are secured to the lower ends of the shoulder strap 12 by the seam 18 which is preferably bound with the tape 15.

The loop straps 17 are then secured together by a rectangular strip of cloth 19 similar to the strip 9 described above and by the horizontal stitchings 20 and the vertical stitchings 21 of the binding tapes 15. In some cases it may be desirable for the stitchings 20 and 21 to extend through the inner fold 13, as illustrated in Figs. 2, 2a and 2b, although it is usually preferable to

have the loop straps free from the inner fold throughout their entire length as described above in connection with Fig. 1 and as shown in the other figures hereinafter described.

It is not necessary that the loop member be attached to the ends of shoulder straps as described above, nor is it always necessary to divide the outer fold of the loop member longitudinally. In Figs. 3, 3a and 3b, for example, the loop member comprises a single folded piece of material having a wide inner fold 22 and a narrower outer fold 23, but the outer fold is not split longitudinally. In this case a pair of vertically spaced loops are formed by means of a rectangular strip of cloth 24 similar to those described above and secured to the outer fold 23 by the horizontal and vertical stitchings 25, the ends of the strip being secured with the edge bindings of the inner fold 22. This loop member is secured in a manner similar to that described above to the lower edge of a back panel 26 which depends from the neck yoke, shoulder straps, etc., as the case may be. In the form shown, the upper edge of the panel is joined to shoulder straps 27.

Figs. 4, 4a and 4b illustrate another construction in which shoulder straps 28 are connected to an intermediate panel 29 which carries a loop member made from a folded single piece of material and comprising inner and outer folds 30 and 31. As shown in Fig. 4, the loop member may be narrower than the panel, instead of being of the same width as illustrated in Fig. 3, and the outer fold 31 is preferably narrower than the inner fold 30. The outer fold is split longitudinally to provide a pair of loop straps 32, but in distinction to Figs. 1 and 2, these loop straps are not laterally spaced. Fig. 4 also shows a further variation in the means used to secure the loop straps together, the rectangular strips of cloth described above being replaced by a rectangle of binding tape 33 secured by stitching 34 to the outer sides of the loop straps.

Figs. 5, 5a and 5b show a further variation in the manner of attaching the transverse dividing strip to the loop straps. The loop member comprises an inner fold 35 and an outer fold which is split longitudinally as in Fig. 1 to provide laterally spaced loop straps 36 the upper ends of which are secured to shoulder straps 37 in a manner corresponding to Fig. 1. The loop straps 36 are secured together by means of a rectangular strip of material 38 similar to the strip 9 of Fig. 1, but matching the material of the loop member with edge bindings 39 matching the edge bindings 40 of the loop member. The horizontal stitchings 41 merely secure the bindings 39 to the strip 38 and do not extend through the loop straps 36, said strip being secured only at its ends which are caught under the edge bindings 40 of the loop straps as indicated at 42. This construction has the advantage that the entire operation of making the loop member can be performed solely on the binding machine.

The construction shown in Figs. 6, 6a and 6b embodies the advantage discussed above in connection with Fig. 5, but the ends of the transverse strip are secured under the edge bindings of the inner fold and the strip is not attached at all to the loop straps. In these figures, the loop member is secured to shoulder straps 43 and comprises a single piece of material folded at the bottom to provide the inner fold 44 and the outer fold 45, the latter being split longitudinally to provide the loop straps 46. The transverse strip 47 and edge bindings 48 are similar to the strip

38 and bindings 39 of Fig. 5, but the ends of this strip 47 are secured under the edge binding 49 of the inner fold 44. The edge bindings 48 are secured to the transverse strip 47 by the horizontal stitchings 50, but this stitching does not extend through the loop straps 46 or inner fold 44 of the loop member. Hence the loop straps 46 and the strip 47 are free of the inner fold 44 as described above.

It will be understood from the foregoing description that the invention is capable of a wide variety of embodiments and is not limited to those particularly described above and illustrated in the drawings, since others may be devised without departing from the spirit of the invention and may be considered desirable by those skilled in the art from the standpoint of appearance, workmanship, etc. For example, the arrangement of the rectangular strip used to form the vertically spaced tie string loops is subject to considerable variation as indicated by the foregoing examples. Further the loop member may be secured to shoulder straps or to an intermediate panel which may in turn be secured to the shoulder straps or to a yoke as shown in my prior Patent No. 1,839,262 mentioned above. The loop member is preferably made from a folded single piece of material, but not necessarily as indicated by the above examples. The outer fold of the loop member is preferably narrower than the inner fold, as this facilitates the insertion of the tie strings at the back of the wearer where the loop member cannot be seen, and when the outer loop is split longitudinally, the loop straps are preferably spaced laterally, but again these features are not essential. Preferably the outer part of the loop member, whether a single strap or spaced parallel straps, is free of the inner fold from top to bottom of the loop member, but as indicated by Fig. 2 this is not necessary in all cases.

It will also be understood that the invention is not limited to aprons but can be used with other garments such as sun suits for women and children, women's and children's aprons and pinnafores, skirt suspenders, and the like.

Other variations from the particular examples described above will be obvious to those skilled in the art, and hence reference should be had to the appended claims for a definition of the limits of the invention.

What is claimed is:

1. A garment of the class described having tie strings adjacent the waist of the wearer, shoulder supporting means, and a depending back section comprising a loop member to which said tie strings are adapted to be secured, said loop member comprising an inner fold adjacent the body of the wearer and an outer fold attached to the inner fold at its top and bottom edges only, said outer fold being of substantially the same width as the inner fold at its bottom edge but tapering upwardly to a substantially narrower top edge, and a separate piece of material secured to said loop member and forming a substantially rectangularly shaped strip of substantial vertical extent which extends transversely across said outer fold adjacent its central section and divides said outer fold into upper and lower loop portions for said tie strings above and below said strip and spaced apart by the vertical extent of said strip.

2. A garment as defined in claim 1 wherein said back section comprises a back panel depending from said supporting means and said loop member is attached to said panel.

3. A garment as defined in claim 1 wherein said supporting means comprises shoulder straps which terminate at and are secured to said loop member.
4. A garment as defined in claim 1, wherein said outer fold is split longitudinally above and below said strip to provide a pair of upper loop portions and a pair of lower loop portions.
5. A garment as defined in claim 1, wherein the inner and outer folds of said loop member comprise a single piece of material doubled over at the bottom of said member.
6. A garment as defined in claim 1 in which the rectangular strip is attached to the outer fold and has its ends secured to said inner fold adjacent the edges thereof.
7. A garment as defined in claim 1 in which the outer fold is split longitudinally to provide a pair of upper loop portions and a pair of lower loop portions, said rectangular strip having its ends secured to said inner fold adjacent the edges thereof.
8. A garment as defined in claim 1 in which the outer fold is split longitudinally to provide a pair of upper loop portions and a pair of lower loop portions, said rectangular strip having its ends secured to said inner fold adjacent the edges thereof but having no connection with said outer fold.
9. A garment as defined in claim 1 in which the outer fold is split longitudinally to provide a pair of upper loop portions and a pair of lower loop portions, said rectangular strip having its ends secured to the outer edges of the split sections of said outer fold.
10. A garment as defined in claim 1 in which the outer fold is split longitudinally to provide a pair of upper loop portions and a pair of lower loop portions, said rectangular strip having its ends secured to the outer edges of the split sections of said outer fold and having its upper and lower horizontal edges secured to said split sections.
11. A garment of the class described comprising a body portion having tie strings adjacent the waist of the wearer, shoulder supporting means, and a depending back section comprising a loop member to which said tie strings are adapted to be secured, said loop member comprising a single length of material doubled over at the bottom and shaped to provide a relatively wide inner fold adjacent the body of the wearer and a relatively narrow outer fold having its upper end connected to said inner fold, said outer fold being split vertically to provide a pair of loop straps and said straps being free of said inner fold throughout their entire vertical extent, and material forming a substantially rectangular strip having substantial vertical extent which extends transversely across the outer sides of said straps substantially midway of their vertical extent, thereby dividing said outer fold into a pair of upper loop portions and a pair of lower loop portions respectively above and below said strip and spaced apart by the vertical extent of said strip.
12. A garment as defined in claim 11, wherein the ends of said rectangular strip are secured to the edges of said inner fold.
13. A garment as defined in claim 11, wherein the ends of said rectangular strip are secured to the edges of said inner fold, but said strip has no connection with said outer fold.
14. A garment as defined in claim 11, wherein

the ends of said rectangular strip are secured to the outer edges of said straps.

15. A garment as defined in claim 11, wherein the ends of said rectangular strip are secured to the outer edges of said straps, the upper and lower edges of said strip being secured to said straps.

16. A garment of the class described having tie strings adjacent the waist of the wearer, shoulder supporting means, and a depending back section comprising a loop member to which said tie strings are adapted to be secured, said loop member comprising a single length of material doubled over at the bottom and shaped to provide a relatively wide inner fold adjacent the body of the wearer and an outer fold which tapers upwardly from the bottom with its upper narrower end secured to said inner fold, said outer fold being attached to said inner fold at its top and bottom edges only, and a separate piece

10
15

of material secured to said loop member and forming a substantially rectangularly shaped strip of substantial vertical extent which extends transversely across said outer fold adjacent its central section and divides said outer fold into upper and lower loop portions for said tie strings above and below said strip and spaced apart by the vertical extent of said strip.
